AUTOMATIC LIFE PRESERVER INFLATOR

Joe Thomas Myers, United States Navy

Application October 10, 1945, Serial No. 621,633

3 Claims. (Cl. 222—5)

(Granted under the act of March 3, 1883, as
amended April 30, 1928; 370 O. G. 757)

11

This invention relates to an automatic life preserver inflator; and in particular to an inflator which is activated by gas pressure operating means which is adapted to quickly release the inflation gas and conduct it into the life preserver, or other inflatable vessels.

Various types of automatic life preserver inflators are known in the art. Some are activated by water pressure on a diaphragm which releases a trigger mechanism thereby activating a plunger or a hammer which punctures the gas container. Some are activated by the oxidation of a wire composed of a material such as magnesium which, when the apparatus is inoperative, holds a spring activated plunger in restrained position. Upon release from this position, the plunger causes the gas containing cartridge to be punctured and the gas therein contained to be released to inflate the preserver. Other types hold the trigger mechanism in inoperative position by means of a soluble element which upon contact with water is dissolved thereby releasing the mechanism to liberate the gas held in a container. These various types in general involve a considerable amount of link work, bearings and pivots which are subject to corrosion so that in many cases the apparatus has been found to be inoperative. Also, in general, too much time is required for the device to operate and to inflate the preserver. Experience has shown that in many cases men with a life preserver in proper position have been drowned due to the slow operation of the inflating mechanism.

With these defects in view it is therefore an object of this invention to provide an apparatus for the inflation of life preservers which is automatic in operation.

Another object of the invention is to provide an apparatus for the inflation of life preservers which is automatic in operation and which is very quickly operable.

A further objection of the invention is to provide an apparatus which is automatic in operation and which is also dependable as to operation.

A still further object of the invention is to provide an apparatus which is automatic in operation and which is adapted to be used with present existing equipment.

An additional object is to provide an apparatus which is automatic and dependable in operation, of simple, strong construction and economical as to manufacture.

These and other objects will be apparent in the following description of one embodiment of the

present invention, in the claims herewith submitted and in the attached drawing which is a longitudinal section through the device. It is partly in section and partly in elevation.

5 Referring to the drawing, 10 represents a valve body which is exteriorly threaded at one end and enlarged at the other end. The interior of the enlarged end is threaded as at 12 to engage the body 13 of a container which is firmly attached
10 to a life preserver adapted to contain the inflation gas cartridge 14. The body of this container is provided with a pointed stud 15 which is adapted to puncture the head of the cartridge when the latter is forced against it. This stud may be
15 fixed or mounted on hand lever operated mechanism as at 11. The container 13 is also provided with a discharge port 17 through which the gas escaping from cartridge 14 passes to the life preserver. Intermediate to this discharge port 17
20 and the life preserver is a check valve mechanism which comprises a hollow metallic stem which is rubber covered. Discharge ports from the metallic stem are positioned underneath this rubber cover which permits the gas under pressure to
25 pass to the preserver but operates as a check against the return. It is a general type of check valve as described by the patent to Muller, No. 1,329,990 issued September 3, 1920. Valve body 10 is provided with shoulder 18 which functions
30 as a guide for plunger 20, the face of which, toward the gas cartridge, is concave to fit the spherical end of the cartridge. The stem of plunger 20 is threaded as at 22 to interfit with piston 24. Piston 24 is provided with an annular groove in
35 its periphery which (groove) supports a neoprene gasket 26 which functions to make a gas tight contact of piston 24 with the walls of body 10. In the space in the body 10 in front of piston 24 is foraminous container for a gas liberating compound such as calcium carbide. This container
40 is adapted to hold substantially one-fourteenth of an ounce of this compound. As is well known when water comes into contact with this compound, acetylene in the form of a gas is liberated.
45 The screen ends of capsule 28 are held in place by spring wires 30 which fit into annular grooves on the inner surface of the capsule. Interfitting the threads on the exterior of the end of body 10 is a cap 31. This cap is provided with a shoulder
50 33 which functions to hold in position water metering valve guide 34 which in combination with the gaskets 32 and 36 is threaded into position against the shoulder. Guide 34 is provided with a tubular boss 38 which functions as a guide for
55 water valve 40. Interposed between the valve 40

and the water metering guide 34 is a coiled spring 42 which normally holds the water valve 40 in seated position as at 43. Water valve 40 is faced with an annular neoprene gasket as at 44 which operates as a gas-tight seal when the device is in operation. There is a port 45 positioned in the end of cap 31 through which water passes when the device is submerged to a sufficient depth. Covering the end of cap 31 is a cover plate 46 which is spaced from the cap 31 by means of bent arms 48 (three in number) which fit into an annular groove in the exterior surface of the cap as at 50.

The operation of the device is as follows:

Upon submersion to a depth of substantially 4 feet, water passes into cover plate 46 between arms 48. It forces water valve 40 away from its seat 43 compressing spring 42. The water then passes through water metering guide 34 and comes into contact with a calcium carbide in the capsule 28. Acetylene gas is immediately generated and develops a pressure within the enclosed chamber sufficient to close valve 40, to drive piston 24, plunger 21 and cartridge 14 with considerable force against pointed stud 15. The gas contained within the cartridge 14 is thereby liberated, passes through port 17 and the check valve mechanism above described into the life preserver. The time required for the inflation is substantially 7 to 10 seconds.

In assembling the apparatus, when the body 10 is screwed into position, there is a tendency to compress the air contained in the assembly which holds water valve 40 tightly in seated position. This condition is removed merely by either opening the valve manually or providing a small airport in cap 31 as at 35. This airport is so positioned as to be covered by the last two threads on body 10.

The device herein disclosed contains few moving parts. They are sealed from contact with the outside air and moisture; hence are not subject to corrosion. The device is therefore dependably operative.

While the foregoing description has been drawn to an embodiment of the invention adapted to the automatic inflation of a life preserver, it is not desired to be strictly limited thereto as the device is capable of being used to automatically inflate any inflatable vessel such as rubber boats, life rafts, position buoys etc.

Furthermore, it can be used for the detection of the presence of water at remote points such as in mines where the movement of the piston or the development of pressure can operate mechanism for recording at a control point.

Such uses and adaptations are within the spirit and scope of the invention to the extent as defined by the herewith appended claims.

The invention described herein may be made and used by or for the Government of the United States for governmental purposes without the payment to me of any royalties thereon or therefor.

What is claimed is:

1. A device adapted to automatically inflate a life preserver by the generation of a mechanism actuating gas pressure therewith comprising a hollow body adapted to be attached to the life preserver and to contain a sealed, inflation gas

cartridge, said hollow body provided with gas cartridge puncturing means and a discharge port adapted to be connected to the interior of the life preserver, a tubular body adapted to be connected to said hollow body, a piston actuated plunger, positioned within the tubular body, adapted to contact the sealed, inflation gas cartridge and to drive it against the puncturing means, a perforate capsule, provided with a compound which generates a gas upon contact with water, positioned within said tubular body in juxtaposition to the piston actuated plunger, a cap adapted to be connected to said cap in spaced relationship thereto, and to permit, when immersed, the water to come into contact with, to exert pressure on, to open and to pass through the said water valve.

2. A device for automatic inflation of a floatable body upon submersion thereof comprising a housing for the device sealed against admission of atmospheric moisture, inflating gas storage means within the housing, hydrostatic valve means within the housing responsive to a predetermined depth of submersion thereof for admitting water to the housing, a gas generating device within the housing constructed and arranged for generation of gas pressure upon admission of water to the housing, means responsive to said generated gas pressure for closing said valve means to retain said gas pressure, means responsive to said gas pressure for releasing said inflating gas from said storage means, and means for conducting said released gas into said floatable body.

3. In a device for automatic inflation of a floatable body upon submersion thereof, a housing for the device sealed against admission of atmospheric moisture, inflating gas storage means within the housing, hydrostatic valve means within the housing responsive to a predetermined depth of submersion thereof for admitting water to the housing, a gas generating device within the housing constructed and arranged for generation of gas pressure upon admission of water to the housing, means responsive to said generated gas for closing said valve means to retain said gas pressure, means responsive to said gas pressure for releasing said inflating gas from said storage means, said last named means being constructed and arranged for manual operation regardless of operation of said hydrostatic valve means, and means for conducting said released gas into said floatable body.
